UNITED STATES PATENT OFFICE.

IRA C. KLINGLER, OF ELKHART, INDIANA.

VALVE MECHANISM.

Application filed April 14, 1924. Serial No. 706,459.

To all whom it may concern:

Be it known that I, IRA C. KLINGLER, a citizen of the United States, residing at the city and county of Elkhart, State of Indiana, have invented certain new and useful Improvements in Valve Mechanisms, of which the following is a specification.

This invention relates to improvements in valve mechanisms.

10 The main object of this invention is to provide an improved mechanism for operating flushing valves for water closet tanks and the like which is simple in its parts, the parts easily assembled upon a tank, and one 15 which is not likely to get out of repair.

Objects pertaining to details and economies of construction and operation will definitely appear from the detailed description to follow.

20 I accomplish the objects of my invention by the devices and means described in the following specification. The invention is clearly defined and pointed out in the claims.

25 A structure which is a preferred embodiment of my invention is clearly illustrated in the accompanying drawing forming a part of this application, in which:

Fig. I is a fragmentary perspective view 30 of a closet tank with my improved valve mechanism mounted thereon.

Fig. II is an inside view partially sectioned on a line corresponding to line 2—2 of Fig. III, the valve lever being shown at 35 one end of its stroke by full lines and at the other end by dotted lines.

Fig. III is a detail view partially in horizontal section.

Fig. IV is a fragmentary inside view corresponding to Fig. II, of a slightly modified form of my invention in which the handle 40 may be completely rotated.

In the drawing similar reference numerals indicate similar parts in all of the views.

45 Referring to the drawing, 1 represents a tank which has an opening 2 therein to receive the non-circular projection 3 of the bracket plate 4. This bracket plate is provided with an inwardly offset arm 5 having a downwardly facing slot 6 therein in which the lever 7 is supported by means of the pivot 8. The pivot is preferably arranged through the arm from the inner side thereof and is provided with a finger piece 9. The bracket plate is secured by the tubular clamping member 10 which constitutes a bearing

for the spindle 11. This clamping member 10 is provided with a head 12 at its inner end, preferably non-circular, and is threaded to receive the clamping nut 13 which is a finishing nut, the wrench in assembling being applied to the non-circular head 12 of the sleeve so that the finishing member or nut 13 is not marred.

The spindle 11 is provided with a crank 65 arm 14 having a pin 15 engaging the longitudinal slot 16 in the lever 7. The top wall of the slot 6 constitutes stops 17 limiting the movement of the lever 7, see Fig. II.

In the embodiment shown in Fig. IV the 70 structure illustrated is the same as that shown in Figs. I, II and III, with the exception that the slot 18 of Fig. IV is of such depth as to allow a complete rotation of the handle 19.

75 In the embodiment shown in Figs. II and III the lever engages the stops 17 when the handle 19 is swung to position shown by dotted lines in Fig. II. This slight modification adapts the structure for either complete rotation or partial rotation of the handle, one type being preferred in some instances and the other in other instances.

With the parts thus formed and arranged 80 they are very economical to produce, and may be quickly assembled upon a tank, the lever constituting a means for preventing longitudinal movement of the spindle so that the parts may be readily disassembled should occasion require.

Having thus described my invention what I claim as new and desire to secure by Letters Patent is:

1. A valve mechanism for tanks comprising a bracket plate having an extension 95 adapted to be inserted in an opening in a tank from the inside thereof and an inwardly offset arm having a downwardly facing slot at its outer end, a clamping sleeve disposed through said bracket plate and having a head engaging the inner side thereof, a clamping nut threaded upon the outer end of said sleeve whereby said sleeve and bracket are secured in position, a spindle arranged through said sleeve and having a crank arm provided with a pin 100 at its inner end and a handle at its outer end, and a lever pivoted in said slot in said arm to project at the side of said crank arm whereby the spindle is supported 105 longitudinally, said lever having a longitudinal slot therein engaged by said pin on 110

said crank arm, the top wall of the slot in said bracket arm constituting stops limiting the swing of said lever.

2. A valve mechanism for tanks comprising a bracket plate having an extension adapted to be inserted in an opening in a tank from the inside thereof and an inwardly offset arm having a slot at its outer end, a clamping sleeve disposed through said bracket plate and having a head engaging the inner side thereof, a clamping nut threaded upon the outer end of said sleeve whereby said sleeve and bracket are secured in position, a spindle arranged through said sleeve and having a crank arm provided with a pin at its inner end and a handle at its outer end, and a lever pivoted in said slot in said arm to project at the side of said crank arm whereby the spindle is supported longitudinally, said lever having a longitudinal slot therein engaged by a pin on said crank arm, the top wall of the slot in said bracket arm constituting stops limiting the swing of said lever.

3. A valve mechanism for tanks comprising a bracket plate having an inwardly offset arm with a downwardly facing slot at its outer end, a clamping sleeve disposed through said bracket plate and having a head engaging the inner side thereof, a clamping nut threaded upon the outer end

of said sleeve, a spindle arranged through said sleeve and having a crank arm provided with a pin at its inner end and a handle at its outer end, and a lever pivoted in said slot in said arm to project at the side of said crank arm whereby the spindle is supported longitudinally, said lever having a longitudinal slot therein engaged by a pin on said crank arm, the top wall of the slot in said bracket arm constituting stops limiting the swing of said lever.

4. A valve mechanism for tanks comprising a bracket plate having an inwardly offset arm with a slot at its outer end, a clamping sleeve disposed through said bracket plate and having a head engaging the inner side thereof, a clamping nut threaded upon the outer end of said sleeve, a spindle arranged through said sleeve and having a crank arm provided with a pin at its inner end and a handle at its outer end, and a lever pivoted in said slot in said arm to project at the side of said crank arm whereby the spindle is supported longitudinally, said lever having a longitudinal slot therein engaged by a pin on said crank arm.

In witness whereof I have hereunto set my hand.

IRA C. KLINGLER. [L.S.]
